UNITED STATES PATENT OFFICE.

HENRY F. CASE, OF SOUTH MANCHESTER, CONNECTICUT.

ELASTIC ROLL.

SPECIFICATION forming part of Letters Patent No. 269,828, dated January 2, 1883.

Application filed October 18, 1882. (No model.)

To all whom it may concern:

Be it known that I, HENRY F. CASE, of South Manchester, in the county of Hartford and State of Connecticut, have invented certain new and useful Improvements in Elastic Rolls; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

My improvement relates to rolls which are required to be used in various sorts of machines where the surface of the roll must be elastic and yielding, this being especially the case with the couching-rolls in cylinder paper-making machines, to which my improvement is particularly adapted.

The object of my invention is to provide a roll which shall have a surface of great elasticity, and at the same time avoid having a longitudinal seam where the elastic covering is joined together.

In the accompanying drawings, illustrating my invention, Figure 1 is a side view of my improved roll with part of the elastic covering removed, so as to show the interior construction and a section of the elastic covering. Fig. 2 is a view of the same turned one-quarter round, and leaving one end of the covering loose to show its construction.

A is the body of the roll. It may be made of wood or of any of the customary materials, and can be turned to any required length or diameter. It has journals or bearings at the ends, adapted to turn in suitable sockets or boxes in the usual manner.

B is the elastic covering. It is made of rubber, and is wound spirally upon the body A, so

as not to present a seam along the length of the roll. At the ends it is to cut tapering, so that when wound it presents a square flat surface at the end of the roll, as shown at the left of the drawings. My improved elastic covering for the roll is composed of the back C, which is of uniform width and flat, and when wound on the roll forms an even and true surface for the outside of the roll, and of the posts D, which are cast or made in one piece with the back C, and are placed at such distances apart as will support the back, at the same time acting as compressible springs to allow it to yield when required. These posts or springs rest directly upon the surface of the body A, and, being all of an exact height, cause the outside to present a true cylindrical form.

My improvement is particularly adapted for the couching-rolls of cylinder paper-making machines. These are the rolls which take the pulp off from the cylinder, upon which it is deposited from the vat, and around which the felt band runs for this purpose. These rolls require to be very yielding and elastic to give a fine and uniform quality to the paper. In addition to this purpose, my improved roll is adapted for any other use requiring a very yielding and elastic surface.

What I claim as my invention is—

1. An improved elastic roll consisting of a central cylinder spirally wound with a rubber covering, provided with the flat back C and the spring-posts D, substantially as described.
2. An elastic covering for rolls, composed of the flat back C and the spring-posts D, attached to its inner surface, substantially as described.

HENRY F. CASE.
